United States Patent Office

Des. 181,092

Patented Oct. 1, 1957

181,092

WASHING MACHINE OR THE LIKE

Carl H. Clement, Jr., Perrysburg, Ohio, assignor to Bock Laundry Machine Company, Toledo, Ohio, a corporation of Ohio

Application January 9, 1957, Serial No. 44,452

Term of patent 14 years

(Cl. D49—1)

FIG. 1.

FIG. 2.

FIG. 3.

FIG. 4.

Fig. 1 is a front perspective view of a washing machine or the like, showing my new design;

Fig. 2 is a side perspective view thereof taken from the left of Fig. 1;

Fig. 3 is a rear perspective of the washing machine, and Fig. 4 is a top plan view thereof on a reduced scale.

I claim:

The ornamental design for a washing machine or the like, substantially as shown.
